UNITED STATES PATENT OFFICE.

THEODORE SCHERF, OF ELIZABETH, NEW JERSEY.

SAND-MOLDING MACHINE.

SPECIFICATION forming part of Letters Patent No. 439,430, dated October 28, 1890.

Application filed July 16, 1890. Serial No. 358,944. (No model.)

To all whom it may concern:

Be it known that I, THEODORE SCHERF, of Elizabeth, in the county of Union and State of New Jersey, a citizen of the United States, 5 have invented certain new and useful Improvements in Sand-Molding Machines, of which the following is a specification.

This invention relates to certain improvements in that class of machines which are 10 used by metal-founders in producing sand-molds for castings, the improvements being designed with a view to prevent the sand from getting access to the working parts of the machine, which necessitates the frequent 15 taking apart of the machine, whereby considerable expense and loss of time is incurred.

The invention consists of a sand-molding machine for metal-founders in which the pattern-supporting block is supported on a spindle that is guided in a box attached to a movable truck or carriage, the pattern being attached to said block and surrounded by a stripping-plate that is supported on standards of the truck-platform. A sand-box is attached 20 to the stripping-plate by means of pins and keepers, so as to inclose the pattern, and a sliding and spring-actuated frame that is adapted to be moved into the sand-box and be locked to the same after it is pressed into the same. 25 A locking-bolt supports the pattern-block and its spindle in raised position for molding, said bolt being unlocked by means of a slide-rod that is actuated by a fixed roller between the track when the machine is moved over the 30 same, said slide-rod having an inclined groove for said roller, while a second roller enters an inclined groove of the spindle and withdraws thereby the pattern-block and pattern from the sand as the truck is moved out of the 35 mold-press.

In the accompanying drawings, Figure 1 represents a side elevation of my improved molding-machine for metal-founders, and Fig. 2 is a vertical longitudinal section of the 40 same.

Similar letters of reference indicate corresponding parts.

Referring to the drawings, K represents a truck or carriage of that class which is used 45 in connection with Tabor's steam-presses for molders. To the truck or carriage K is applied a table or platform J, to which all the

supporting parts of my improved molding-machine are attached. Upright standards E are attached to the table J, said standards supporting at their upper ends a stripping-plate F, which is provided with an opening that corresponds to the size of the pattern, so as to permit the passage of the same through the stripping-plate. The pattern A is screwed 55 onto a pattern block or plate B, which is supported on a spindle C, that is guided in a box D, attached to the table J. A spiral spring H is interposed between the under side of the pattern-block B and the upper edge of the 60 box D, said spring lifting the pattern-block and the pattern thereon after the same has been withdrawn from the sand.

On the stripping-plate F is supported a sand-box D', which is kept in place by means 70 of fixed guide-pins V, which enter keepers W, attached to the sides of the sand-box D. The sand-box D' is made of wood in the usual manner. In the sand-box D' slides a frame D², which is beveled at its lower edge, and 75 which is provided with horizontal projections p, against which press spiral springs S, the lower ends of which are supported in sockets of the sand-box D', as shown in Fig. 2. The sand-box D' is preferably made of two parts, 80 which are connected by hinges at one corner and connected at the diametrical corner. The sliding frame D² is engaged by means of spring-catches r when it has been pressed into the sand-box D', said catches holding the 85 frame D² in its lowest position in the sand-box D until the mold is removed from the box D'. When this is accomplished, the spring S will readily return the sliding frame D² into its raised position, ready for the next molding 90 operation. The spindle C is provided with a recess or socket g, that is engaged by a sliding bolt G, by which the pattern-plate and spindle are locked in position, while the sand is compressed in the press. A vertical slide-rod 95 L, having a beveled upper end, engages an anti-friction roller g' of the slide-bolt G, and withdraws the same from the recess or socket g of the spindle C against the tension of a spiral spring g², placed around the shank G' 100 of the bolt G, as shown clearly in Fig. 1. The upward motion of the slide-piece L is accomplished by means a roller N, which is located midway between the supporting rails

of the track on which the truck J is moved to and from the press, said roller engaging an inclined recess X in the side of the slide-rod L, so as to raise thereby the slide-rod and withdraw the slide-bolt G. The slide-bolt G and its shank G' are guided in an opening of the box D on the top of the truck K and in an opening of one of the standards E, the bolt being only actuated when the molding-machine is removed from the press. A second roller, which is located on the transverse pivot of the roller N, engages a side recess Y at the lower end of the spindle, which recess is inclined in a direction opposite to that of the recess X of the slide-rod, so as to move thereby the spindle C and the pattern-block B in downward direction for lowering the pattern and removing it from the sand molded around the same in the box D.

20 The operation of my sand-molding machine is as follows: The pattern is screwed into position on the pattern-plate B and the spindle C locked in position by the slide-bolt G, so that the pattern projects into the sand-box D'. Sand is then shoveled into the sand-box D', and the truck is then moved under the press and the slide-frame D² pressed downward by the follower of the press into the box D' until the catches r engage the lugs p of the frame D² and retain the same in position in the box D'. The sand is thereby compressed around the pattern and the mold formed thereby. The molding-machine is then moved away from under the press, and during the forward motion the slide-rod L is first actuated and the slide-bolt G withdrawn by the action of the roller N, so as to unlock the spindle C, while by the second roller the spindle C, and thereby the pattern-block B, is lowered and the pattern A removed from the mold in the sand-box. The sand mold is then removed from the box D' by releasing the catches so that the frame D² is raised. The sand-box is now filled up again, and the spindle C and pattern-block B returned to their normal position and relocked again by the slide-bolt G, after which sand is shoveled into the box and the molding machine returned with its truck to the press, whereby by the next operation the pressing and molding of the sand takes place. Owing to the slow withdrawal of the pattern from the sand the sand cannot stick to the patterns nor the edges of the mold be broken off, because when the pattern is pulled downward the sand mold rests on the straight stripping-plate F, whereby a perfect mold is obtained without any injury to the same. The sand cannot interfere with any part of the machine, for in case any particles of sand should get loose they would

drop downward, so that they can be readily blown out, as the apparatus is made open at the sides around the spindle C, which is protected by its guide-box D and table J. As the sand does not block the machine, it performs its work regularly and in a reliable manner without taking the parts apart. Reliable sand molds are thus obtained in less time and with less work as compared to other machines of this kind heretofore in use. 70

Having thus described my invention, I claim as new and desire to secure by Letters Patent—

1. The combination of a supporting truck or carriage having a table attached to the same, a stripping-plate supported on standards of said table, a pattern-block, a vertically-sliding and spring-actuated spindle for supporting said pattern-block, means for locking said spindle to the truck, a sand-box resting on the stripping-plate and retained thereon, a spring-actuated slide-frame guided in the sand-box, and means for locking said slide-frame when forced into the sand-box by the press, substantially as set forth. 85

2. The combination, in a sand-molding machine, of a pattern-block and its supporting spindle, a truck, a vertical slide-rod having a beveled upper end guided on the table of said truck, a spring-actuated slide-bolt adapted to lock the spindle, and a roller located between the supporting-rails of the track and adapted to engage an inclined recess of the slide-rod so as to lift the same and withdraw the bolt when the pattern is to be withdrawn from the mold, substantially as set forth. 90

3. The combination of a supporting truck or carriage, a table on the same, a stripping-plate supported on standards of said table, a pattern-block, a pattern attached to said block, a spindle for supporting the pattern-block, a guide-box on the table of the truck for guiding said spindle, a spiral spring interposed between the pattern-block and the top of the guide-box, and a roller intermediately between the supporting-rails of the track, said roller being adapted to engage an inclined recess at the lower end of the spindle for lowering the same and withdrawing the pattern from the mold when the machine is removed from the press, substantially as set forth. 100 105 110

In testimony that I claim the foregoing as my invention I have signed my name in presence of two subscribing witnesses.

THEODORE SCHERF.
